UNITED STATES PATENT OFFICE.

WALTER E. SALSMAN, OF MOUNTAIN VIEW, MISSOURI, ASSIGNOR OF ONE-TENTH TO
LINA CRABTREE, OF MOUNTAIN VIEW, MISSOURI.

RAIL-JOINT.

1,238,442.

Specification of Letters Patent. Patented Aug. 28, 1917.

Application filed June 9, 1917. Serial No. 173,780.

To all whom it may concern:

Be it known that WALTER E. SALSMAN, a citizen of the United States, residing at Mountain View, in the county of Howell 5 and State of Missouri, has invented certain new and useful Improvements in Rail-Joints, of which the following is a specification, reference being had to the accompanying drawings.

10 This invention relates to rail joints, and the general object of the invention is the provision of a very simple and cheaply constructed rail joint which will be entirely effective in holding the abutting rails in 15 engagement with each other and which will also act as an electric bond between the rails.

A further object is to provide a construction of this character whereby the rails may 20 be readily connected to or disconnected from each other and in which the joint may be made when the rails are rolled.

Other objects will appear in the course of the following description.

25 My invention is illustrated in the accompanying drawings, wherein:—

Figure 1 is a longitudinal sectional view of two abutting rails connected by my improved joint;

30 Fig. 2 is a side elevation of the rails and joint, the bolt being in section;

Fig. 3 is an elevation looking from the opposite side of the joint; and

35 Fig. 4 is a perspective view of the two rails separated.

Referring to these figures, 10 and 11 designate abutting rails of the usual form. The rail 10 is formed adjacent its end with a transverse aperture 12. The rail 11 is also 40 formed adjacent its end with a transverse aperture 13, which is preferably rectangular in form. Formed integral with the web of the rail 10 is a tongue 14, the extremity 15 of which is laterally bent and preferably 45 ductile. The web of the rail 11 is formed with a tongue 16, which is not flexible, but at its end is recessed as at 17.

In the practical use of this invention, the rails 10 and 11 are abutted against each 50 other and the angular extremity of the tongue 14 is inserted through the perforation 13, while the tongue 16 is disposed

against the web of the rail 10. A bolt 18 is passed through the perforation 12, said bolt being provided at one end with an enlarged 55 head 19 and at its other end with a nut 20. This enlarged head bears against the bifurcated extremity of the tongue 16, so as to hold this tongue 16 flat against the web of the rail 10 and in tight engagement therewith. This tongue 16 might be formed with a perforation, instead of the notch 17, for the passage of the bolt 18. When the parts are thus joined, the extremity of the tongue 15 is turned flat against the outer face of 60 the tongue 16, as illustrated in Figs. 1 and 2 and the rails are thus held in conjoined relation.

It will be seen that this construction provides for a very simple manner of connecting the rails, that it holds the rails firmly 70 together and yet allows for expansion and contraction and furthermore that it forms a perfect bond between the rails so that the rails may be used for electric railways. It 75 will also be seen that there are no bolts to shear, that no strain comes upon the bolt 12, but that the two tongues 14 and 16 hold the rails in exact alinement with each other.

Having described my invention, what I 80 claim is:

1. In a rail joint, abutting rails, one of the rails being formed with a perforation and a tongue on the other rail adapted to be disposed through said perforation and bent 85 against the web of the perforated rail to thereby hold the rails in abutting relation.

2. In a rail joint, abutting rails, the web of each of said rails being formed with a perforation adjacent its end, an angular 90 tongue formed upon one of the rails, the extremity of the tongue being relatively flexible, the extremity being adapted to be inserted through the perforation in the web of the other rail and then bent flat against 95 the rail, the second named rail being formed with a tongue adapted to be engaged against the web of the first named rail, the tongue being notched at its end, and a bolt passing through the perforation of the second named 100 rail and through the notch of said tongue.

3. In a rail joint, abutting rails, one of said rails being formed with a perforation through its web adjacent its extremity and

with an integral tongue projecting from the end of the rail on one side face thereof, the tongue being angularly bent, the other rail being formed upon the opposite side face 5 with a tongue and having a perforation through its web through which the angular end of the first named tongue is adapted to engage, and a bolt passing through the

perforation in the first named rail and engaging the tongue of the second named rail. 10

In testimony whereof I hereunto affix my signature in the presence of two witnesses.

WALTER E. SALSMAN.
